UNITED STATES PATENT OFFICE.

JOHN B. WHITTED, OF ELIZABETHTOWN, NORTH CAROLINA.

ROTARY ENGINE.

1,239,752.

Specification of Letters Patent. Patented Sept. 11, 1917.

Application filed April 7, 1915. Serial No. 19,829.

To all whom it may concern:

Be it known that I, JOHN B. WHITTED, a citizen of the United States, residing at Elizabethtown, in the county of Bladen and State of North Carolina, have invented a new and useful Rotary Engine, of which the following is a specification.

The device forming the subject matter of this application is a rotary engine, and one 10 object of the invention is to provide novel means whereby a trapped quantity of fluid is permitted to act by expansion upon one of the pistons as the rotor moves.

Another object of the invention is to improve 15 the construction of the rotor and its parts.

A further object of the invention is to provide novel means whereby the engine may be reversed.

20 It is within the province of the disclosure to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

In the accompanying drawings:

35 Figure 1 is a vertical section wherein divers parts appear in elevation;

Fig. 2 is an elevation showing one of the end plates;

Fig. 3 is an end elevation;

40 Fig. 4 is a diagram referred to in explaining the workings of the engine;

Fig. 5 is a cross section;

Fig. 6 is a perspective detail showing a part of the rotor;

45 Fig. 7 is a perspective detail showing a part of one of the rotor pistons.

The rotary engine forming the subject matter of this application comprises a stator including a base 1 supporting a ring or body 2 co-operating with end plates 3 equipped in their inner faces with annular grooves 4 and provided with cam ribs 5.

50 The rotor includes a shaft 6 journaled in bearings 7 on the end plates 3, and an annular member comprising a hub 8 secured to the shaft 6, a rim 9, the edges of which

are received in the grooves 4, and a web 10 connecting the hub 8 with the rim 9. In the side faces of the rim 9, packings 11 are located, the same being actuated outwardly 60 by means of springs 12 to co-operate with the walls of the grooves 4 in which the edges of the rim 9 are received.

The rim 9 and the web 10 of the rotor are provided with any desired number of radial slots 14 in which are mounted to slide radially, pistons denoted generally by the numeral 15, each piston 15 comprising a head 16 and a reduced stem 17 defining shoulders 18 which coact with the cam ribs 5, to advance and retract the pistons 15. The rim 9 is provided with packings 19 disposed transversely, and adapted to co-operate with the pistons 15, the packings 19 being advanced against the pistons by means of 75 springs 20. Springs 21 co-operate with the hub 8 and the shoulders 18 on the pistons 15 and constitute means for advancing the pistons. Pivoted to the outer ends of the pistons 15 are closures 22 adapted to co-operate 80 with the ring or body 2 of the stator.

The body or ring 2 of the stator is provided with abutments 23 carrying movable packings 24 advanced by springs 25. The packings 24 may be lubricated by means of 85 cups 26. The abutments 23 lie within the contour of casings 27, the numeral 28 indicating outwardly extended partitions within the casings. Assembled with or constituting a part of the casings 27 are steam inlet chambers 29. Ports 30 and 31, disposed upon opposite sides of the respective partitions 28 establish communication between the steam inlet chambers 29 and the casings 27, there being ports 32 and 33 which lead from the 95 casings 27 into the interior of the stator, the ports 32 and 33 being located upon opposite sides of the respective abutments 23.

The fluid pressure supply pipe is denoted by the numeral 34 and comprises branches 35 which open into the steam inlet chambers 29. Exhaust pipes 36 are shown, the same having branches 37 opening into the stator above the abutments 23, the exhaust pipes 36 further including branches 38 which open 105 into the stator below the abutments 23. The exhaust pipes 36 comprise branches 41 and 42 opening into the respective casings 27 upon opposite sides of the abutments 23. The exhaust branch 37 is controlled by a valve 110 43 having an opening 44. This valve like other valves to be mentioned hereinafter is

shown as slidably mounted, but the specific form of valve may possibly be departed from without jeopardizing the utility of the invention. In each of the casings 27 is 5 mounted a slide valve 45 having an opening 46 adapted to coincide with the port 30 or with the exhaust branch 41. In each valve 45 there is formed an opening 47 adapted to coincide with the port 31 or with the exhaust branch 42. The exhaust branch 38 is controlled by a valve 48 having an opening 49.

The means for operating the several valves above outlined embodies the lever 50 which 15 may be fulcrumed as shown at 51 on one of the bearings 7. Assembled with the lever 50 is an arcuate frame 52 carrying a handle 53 adapted to coöperate with a segment 54 or with any other suitable form of latch 20 mechanism. The lever 53 is connected with the frame 52 by means of a brace 55. Links 56 connect the ends of the lever 50 with the upper and lower ends of the valves 45 and by means of links 57, the valves 45 are connected with the valves 48 and 43.

For the purpose of introducing oil into the stator between the cam ribs 5 and the grooves 4, the end plates 3 are provided with openings 58 controlled by movable closures 59. The oil thus introduced into the stator 30 serves to lubricate the working parts and surplus or vitiated oil may be drawn away through pet cocks 60.

Assuming that the rotor is moving in the 35 direction of the arrow in Fig. 1, the positions of the various valves are as follows:—

The valve 43 closes the exhaust branch 37, the valve 45 closes the exhaust branch 41, the opening 46 in the valve 45 coinciding 40 with the port 30, thereby to open the port 32, the valve 45 closing the port 31, and the opening 47 in the valve 45 coinciding with the exhaust branch 42. The opening 49 in the valve 48 coincides with the exhaust 45 branch 38. The foregoing description applies to the right hand side of the engine as shown in Fig. 1, and on the left hand side of the engine, the positions of the various valves are reversed from that described. Referring to the right hand side of the 50 engine, steam enters the pipe 34, traverses the branch 35 and enters the casing of the stator by way of the ports 30 and 32, the steam or other fluid which traverses the top of the stator being discharged through the upper left hand pipe 37 which is open. Observing that the port 32 and the exhaust branch 41 at the left hand side of the engine are 55 open, it will be obvious that back pressure on the pistons 15 is avoided.

The pistons 15 are advanced and retracted by the action of the shoulders 18 of the pistons 15, on the cam ribs 5, the springs 21 serving to aid in advancing the pistons.

65 Let reference be had at this point to the

diagrammatic figure which is numbered 4. Two of the pistons are designated by the reference characters A and B. Steam entering the compartment C through the port 32 acts on the effective pressure surface D 70 of the piston A to turn the rotor in the direction of the arrow. A quantity of steam is trapped in the compartment E between the piston A and the piston B, it being noted that the piston B has not yet arrived 75 at the open exhaust pipe 37. Since the effective surface pressure F of the piston B is greater than the effective working area D of the piston A, and since the piston A is actuated by live steam, the steam trapped in 80 the compartment E will be permitted to expand against the working area F of the piston B, thereby aiding in propelling the rotor.

It is to be understood that the parts are 85 so proportioned in practice that the compartment E is of constantly increasing size as the rotor turns on its axis.

When it is desired to reverse the engine, such an operation is brought about by shifting the lever 53, the same actuating the lever 50, motion being transmitted by the links 56 to the valves 45 and from the valves 45 by way of the links 57 to the valves 43 and 48 respectively. Owing to the fact that this 95 specification is addressed to persons skilled in the art, it is not necessary to trace out the steam and exhaust conduits after the engine has been reversed, since the relative positions of the valves with respect to each 100 other and to the openings or ports which they control will be obvious to one skilled in the art having before him the disclosure of Fig. 1.

Having thus described the invention, what 105 is claimed is:—

1. In a device of the class described, a stator comprising end plates; cam ribs on the end plates; a rotor journaled in the stator; pistons slidably in the rotor, each piston comprising a head and a reduced stem defining shoulders in the piston; and springs disposed upon opposite sides of the stem, the springs engaging at their outer ends with the shoulders and engaging at their 115 inner ends with the stator, the inner edges of the shoulders coacting with the cam ribs.

2. A rotary engine comprising a stator having oppositely disposed abutments and provided at each side with a pair of first 120 exhaust ports, the exhaust ports of the pairs being located upon opposite sides of the respective abutments, the stator being supplied at each side with a pair of second exhaust ports located between the first exhaust ports 125 of each pair, the stator being equipped at each side with a pair of inlet ports disposed on opposite sides of the respective abutments and between the second exhaust ports of each pair; main valves mounted on the 130

stator for right line sliding movement, each main valve controlling one pair of inlet ports and a corresponding pair of second exhaust ports; an auxiliary valve controlling each first exhaust port and mounted on the stator for right line sliding movement; links pivotally connected to the outer ends of the main valves and with the inner ends of the corresponding auxiliary valves; a single lever fulcrumed intermediate its ends on the stator; means for holding the lever in

adjusted positions; a link connecting each end of the lever with one of the main valves; and a rotor journaled in the stator and co-operating with the abutments.

In testimony that I claim the foregoing as my own, I have hereto affixed my signature in the presence of two witnesses.

JOHN B. WHITTED.
